REFRIGERATING APPARATUS

John W. Craig, Dayton, Ohio, assignor to General Motors Corporation, Dayton, Ohio, a corporation of Delaware

Application February 28, 1938, Serial No. 192,991

6 Claims. (Cl. 62—118)

This invention relates to refrigerating apparatus and more particularly to intermittent absorption apparatus employing a re-absorber instead of the usual evaporator.

It has been found that the efficiency of intermittent absorption refrigerating systems can be increased if instead of the usual evaporator, a second generator absorber is used which liberates the refrigerant at a comparatively low temperature. In such systems it is customary to provide a secondary refrigerant system in heat exchange relation with the low temperature generator absorber for dissipating the heat of association in the low temperature generator absorber during the generating cycle. With many installations it has been rather difficult to provide a simple scheme for such a system, since some means must be provided for conducting the liquid, which is liquefied in the condenser of the secondary system to the cooling unit or the low temperature generator absorber.

It is an object of my invention to provide an improved means particularly adaptable to household refrigerators for returning this condensed liquid in the secondary system to the cooling unit.

It is another object of my invention to provide an improved intermittent absorption refrigerating system employing a re-absorber as a cooling unit in which substantially the entire mechanism may be placed below the cooling unit.

It is still another object of my invention to provide a heat pump operated by the burner, which is also used to heat the high temperature generator-absorber, for pumping the liquid from the condenser in the secondary system to the cooling unit.

Further objects and advantages of the present invention will be apparent from the following description, reference being had to the accompanying drawing, wherein a preferred form of the present invention is clearly shown.

In the drawing:

The figure is a diagrammatic illustration of a household refrigerator cabinet provided with an intermittent absorption refrigerating machine employing a low temperature reabsorber as a cooling unit.

Briefly I have provided an intermittent absorption system for a household refrigerating system in which the cooling unit forms a part of a secondary refrigerant system connected to a condenser in the machine compartment and a liquid pump heated by the burner of the high temperature generator-absorber is provided for pump-

ing the liquid from the condenser up to the cooling unit.

Referring now to the drawing there is shown a domestic refrigerator cabinet 20 provided with a food storage compartment 22 and a machine compartment 24 located beneath the food storage compartment. The machine compartment contains a generator-absorber 26 connected by a refrigerant conduit 28 with an inter-lock control means 30 which in turn is connected by a refrigerant conduit 32 with a pressure controlled valve means 34 which provides substantially no resistance to the flow of refrigerant driven off from the generator-absorber 26 to the refrigerant conduit 36 which connects to a low temperature generator-absorber 38 located within an insulated compartment 40 of the cooling unit 42.

The cooling unit 42 is provided with ice tray compartments 44 which are surrounded by refrigerant ducts 46 which depend from the insulated compartment 40 which contains a secondary heat transfer liquid 48 in the form of a bath in which is supported the low temperature generator-absorber 38. The insulated compartment 40 containing the secondary refrigerant liquid 48 is provided at its upper portion with a vapor conduit 50 which extends through the rear wall of the cabinet and thence down the back wall of the cabinet to a tube and fin type condenser 52 where the evaporated secondary refrigerant may be condensed.

The condenser 52 drains through a conduit into a heat operated liquid pump 56 provided with a check valve 54. The liquid pump 56 is located over one end of the burner 58 so that it is heated during any operation of the burner. This heat causes the liquid to be forced upwardly through the liquid conduit 60 by means of the vapor pressure created in the chamber of the liquid pump 56 by the heat from the burner 58. This conduit 60 is provided with fins along the back wall of the cabinet for cooling the liquid before it is discharged within the insulated chamber 40 over the surfaces of the low temperature generator-absorber 38. In this way the evaporated refrigerant is condensed and then returned to the cooling unit during each operating period of the burner 58.

The burner 58 is provided with a pilot light 62 and the burner, but not the pilot light, is supplied with gas through conduit 64 under the control of a snap acting valve 66. The generator-absorber 26 is provided with a volatile liquid vapor heating and cooling system which includes a jacket 68 which surrounds the generator-ab-

sorber 26 and is exposed to the products of combustion from the burner 58 in order to assure uniform heating of the generator-absorber 26. The upper portion of this jacket 68 is connected by a vapor conduit 70 to a pressure operated valve 72 which controls the flow of vapor to a fin and tube type condenser 74 located above the generator-absorber. The bottom of the condenser 74 is connected by a liquid drain conduit 76 with the bottom of the jacket 68. The pressure operated valve 72 is employed to operate the snap acting gas valve 66 and they are connected by a lever 80 provided with a snap acting mechanism 82, and a latch mechanism 84 which forms a part of the inter-lock 30.

As shown in the drawing the system is shown in the midst of the absorption cycle. The gas valve 66 is closed and the valve 72 is open permitting the volatile liquid in the jacket 68 surrounding the generator-absorber 26 to vaporize and pass through the valve 72 to be condensed in the condenser 74 from which the condensed volatile liquid may drain back to the jacket 68. In this way the generator-absorber is cooled and under such conditions the vapor pressure in the conduits 28 and 32 will be reduced to such a low pressure that refrigerant will be drawn through the valve 34 from the conduit 36 which connects to the low temperature generator-absorber 38.

This lowers the vapor pressure at the low temperature generator-absorber 38 causing the disassociation of the refrigerant from the absorbent therein. This is an endothermic reaction and requires the addition of heat to permit it to continue. This heat is removed or taken from the liquid and vapor in the secondary refrigerant system which in turn through the medium of the depending ducts 46 removes heat from the water in ice trays which may be placed within the ice tray compartments 44 and also from the air within the food storage compartment 22.

A spring 86 acts upon the lever 80 to tend to close the valve 72 and to open the gas valve 66. This, however, is prevented by the latch 84 of the inter-lock 30 until such time as the generator-absorber 26 fails to maintain a sufficiently low pressure within the conduits 28 and 32 to provide refrigeration at the cooling unit. When this limit is reached the pressure within the inter-lock becomes sufficiently great to move the latch member 84 downwardly to release the lever 80 and allow the spring 86 to overcome the snap acting mechanism 84 and to move the gas valve 66 to open position as well as to move the vapor valve 72 to closed position.

This stops the absorption cycle and begins a new generator cycle. The gas flow through the opening valve 68 to the gas burner 58 which heats the volatile liquid in jacket 68 to heat the generator-absorber 26. This drives the refrigerant from the generator-absorber 26 through the conduits 28, 32 and 36 to the low temperature generator-absorber 38. Here the low temperature generator-absorber absorbs the refrigerant only by the evolution of heat which causes the secondary refrigerant 48 to boil and causes the vapor to pass through the conduit 50 downwardly to the condenser 52 where it is condensed and drains into the liquid pump 56. Since the burner 58 is in operation liquid will be pumped upwardly through the conduit 60 and cooled by the fins thereon in its upward passage to the insulated chamber 40 of the cooling unit where it dis-

charges over the warm low temperature generator-absorber 38.

The valve 34 serves to regulate the pressures which are maintained within the secondary generator-absorber 38 during the absorption cycle so as to regulate the temperature of the evaporating means 22. An adjustment may be provided for the loading of this valve in order to change the pressures which are maintained in the low temperature generator-absorber during this portion of the cycle for the purpose of providing a temperature adjustment.

As absorbents I prefer to employ manganese chloride in the high temperature absorber and barium chloride in the low temperature absorber 38 with ammonia as the refrigerant. The use of these absorbents permit the air cooling of the low temperature absorber 38 during the generating cycle and the air cooling of the generator-absorber 38 during the absorption cycle, even during the warmest weather normally encountered. The secondary circuit may contain any suitable volatile liquid which does not congeal but acts as described above, such as sulphur dioxide or difluorodichloro methane.

While the form of embodiment of the invention as herein disclosed, constitutes a preferred form, it is to be understood that other forms might be adopted, all coming within the scope of the claims which follow.

What is claimed is as follows:

1. Refrigerating apparatus including a generator-absorber, a cooling unit, a secondary refrigerant system in heat exchange relation with said cooling unit, said secondary refrigerant system having condensing means located below said cooling unit, pumping means for pumping liquid collected in a lower portion of said secondary system up to said cooling unit, and heating means for heating the generator-absorber and also for operating said pumping means.

2. Refrigerating apparatus including a generator-absorber, a cooling unit, a secondary refrigerant system in heat exchange relation with said cooling unit, said secondary refrigerant system having condensing means located below said cooling unit and pumping means for pumping liquid collected in a lower portion of said secondary system up to said cooling unit, said cooling unit including a second generator-absorber connected by conduit means with said first mentioned generator absorber.

3. Refrigerating apparatus including a generator-absorber, a cooling unit, a secondary refrigerant system in heat exchange relation with said cooling unit, said secondary refrigerant system having condensing means located below said cooling unit and pumping means for pumping liquid collected in a lower portion of said secondary system up to said cooling unit, said cooling unit including a second generator-absorber connected by conduit means with said first mentioned generator-absorber, said pumping means being operated by the heating means for the first mentioned generator-absorber.

4. Refrigerating apparatus including a generator-absorber, a cooling unit, a secondary refrigerant system in heat exchange relation with said cooling unit, said secondary refrigerant system having condensing means located below said cooling unit and pumping means for pumping liquid collected in a lower portion of said secondary system up to said cooling unit, said cooling unit including a second generator-absorber connected by conduit means with said first men-

tioned generator-absorber, said pumping means being operated by the heating means for the first mentioned generator-absorber, said first mentioned generator-absorber containing a high 5 temperature absorbent and said second generator-absorber containing a lower temperature absorbent.

5. Refrigerating apparatus including a generating means, a secondary refrigerant circuit having 10 a condensing portion and an evaporating portion, said evaporating portion being located above said condensing portion, said secondary circuit being provided with pumping means for lifting liquid from the level of said condensing

portion to the level of said evaporating portion, and a heating means for heating said generating means and for operating said pumping means.

6. Refrigerating apparatus including a generator-absorber, a cooling unit, a secondary refrigerant system in heat exchange relation with said cooling unit, said secondary refrigerant system having condensing means located below said cooling unit, pumping means for pumping liquid collected in a lower portion of said secondary system up to said cooling unit, and means for intermittently heating said generator-absorber and said pumping means. 5 10
